AIR FILTER LOADER

Thomas R. Hughes, Louisville, Ky., assignor to
 American Air Filter Company, Inc., Louisville, Ky., a corporation of Delaware

Application April 5, 1937, Serial No. 135,100

10 Claims. (Cl. 93—1)

It has been heretofore proposed to provide an air-filter unit composed of a removably securable pair of unitary open-ended mating frames, the mating-end faces of opposed frames having corrugations which nest into each other in mating relation. The corrugated mating face of each frame is formed by serrating two of its laterally opposed outer side walls to provide correspondingly opposed fingers extending in the direction of air flow, the space between adjacent fingers on each serrated wall being open on both sides, i. e., laterally inward and outward. When the frames are mated, the fingers nest into each other in non-telescoping abutting relation. In use a sheet of air filtering material is interposed between and conformed in shape to the corrugated faces of the mating frames. After a suitable period of use the mating parts of the unit are separated, the soiled sheet of filtering material removed and the unit provided or loaded with a clean sheet. The present invention relates to a novel device for loading this character of filtering unit, that is to say for conforming a sheet of filtering medium to the corrugations of the mating face of one of the frames, whereby such frame is conditioned to receive the other frame and thus made ready for use.

The principal object is to provide a simple and highly practical device for loading the corrugated face of a filter unit frame and one which is capable of easy and quick operation to load one or a succession of such frames.

Another object is to provide a novel device which functions to move the frame and to feed and conform the filtering material to it.

A further object is to provide a novel arrangement by which the size of the device is minimized for packaging and handling purposes and yet remains capable of easy and quick extension to a larger size which may be more suited to its normal use.

One embodiment of the invention is shown in the accompanying drawings wherein:

Figure 1 is a top plan view of the device with a track extension member detachably secured at one of its ends;

Figure 2 is a section along line 2—2 of Figure 1;

Figure 3 is a plan view of the guide channel plate; and

Figure 4 is a section similar to the one shown in Figure 2 but with a filter unit frame in partly loaded position.

Frame

55 The illustrated embodiment of the invention

comprises a frame composed of a flat horizontal base member 1 and a pair of vertical side members 2, all of which are suitably secured together to form a frame which is U-shaped in cross section. These members, which preferably are made of heavy sheet metal, may be reinforced by arranging a pair of struts 3 between and securing their opposite ends to the upper ends of the side members 2 to hold such members rigidly in spaced relation.

5 10

Track and track extension

A frame-supported track, upon which an air filter of the type having a corrugated support for the filter medium may be movably supported, is arranged between the side members 2 above the base 1. This track includes a pair of spaced track members 4, one being horizontally arranged along each side member 2. Each track member 4 is spaced inwardly from, and secured at its opposite ends to, its corresponding side member 2. The track, may, of course, be of any length considered desirable but, to minimize the size of the device and thus facilitate its packaging and handling, the track members 4 are terminated at the opposite ends of the frame. Since that length of track may be inconveniently small during use, it is proposed to increase it by providing, for each end of the frame, a track extension which may be detachably secured to the frame. Such extension may consist of an auxiliary frame 1a and a pair of auxiliary track members 4a supported thereon in proper spaced relation. It can be detachably secured to the frame 1 in any suitable manner as by providing it, at one end, 20 25 30 35 with a pair of hooks 5 to hook detachably over a corresponding pair of pintles 6 on the frame 1.

Filtering material

The filter unit frame or member F, whose corrugated face is to be covered by a conforming sheet of filtering material, is, of course, to be moved along the track with its corrugated face facing outwardly or upwardly and with one of its straight marginal edges, as distinguished from its corrugated marginal edges, forward so that its corrugations extend sequentially in the direction of movement i. e. one after another in the line of motion. The filtering material may be cut in sheets of desired length and placed over the corrugated face but preferably is fed from a roll 7 to the corrugated face as the unit is moved through the device. While such a roll may be supported in any desired way the upper ends of the side members provide a convenient support 40 45 50 55

and are therefore notched at 8 to receive a roll supporting rod 9.

Operating bars and guide channels

5 In further accordance with my invention means are provided, at what may be termed the "loading area" of the device, to press successive portions of the filtering medium fed from the roll 7 into conformation with successive corrugations of the filter unit member and to hold one portion of the material in conformation with its corrugations during the interval in which another portion is being pressed into conformation with another corrugation. Such means includes a 10 series of operating elements or bars 10 extending cross-wise, i. e., transversely with respect to the line of filter-unit motion, above the track with their opposite ends engaged in guiding channels 11. Any number of bars, as are found desirable 15 or necessary, may be used but excellent results can ordinarily be obtained with only four bars, as illustrated. The guiding channels 11 cooperate to form, and to direct the bars 10 successively along, an endless path having the following successively arranged portions; a pressing portion 20 which extends into the loading area and down to the bottom plane of the corrugations of a filter-medium support moving along the track; a holding portion which extends forwardly substantially along such plane for a distance not appreciably less than the pitch of said corrugations; an exit portion which extends from the holding portion outwardly beyond the loading area; and a return portion which extends from 25 the exit portion back to the pressing portion. During the inward travel of one bar along the pressing portion, one portion of the medium is pressed by it inwardly into a corrugation. During the forward travel of such bar, such portion is held in conformation with such corrugation so as to permit the next bar to press the next portion of the material into conformation with the next corrugation without pulling the material from the preceding corrugation. It will be understood, of course, that the downward and upward portions of the channels 11 are made to 30 extend obliquely forward sufficiently to accommodate the forward movement of the filter unit.

Sequence of bar movement

50 In order to move the bars in their ordered sequence along the channels 11, a rotatable control part or wheel 12 is placed over each channel and centered slightly outward from or above the bottom portion thereof. Each control part or wheel contains a number of uniformly spaced, outwardly extended slots 13, one for each bar 10. Each slot extends, from a point adjacent the center of the wheel, radially outward for a distance sufficient to cross the bottom portion of the channel when brought over it and thence curves concavely outward in a direction which brings its outer end to a substantially lagging position relatively to the outer end of the radius along which its radial inner portion extends. In this manner the bars are made to travel rapidly in the upper sections of the channel as compared with their travel in the lower sections thereof.

Drive

70 With the foregoing arrangement it is necessary to drive the wheels 12 since their rotation cannot very well be effected by manually pushing or shoving the filter unit frame through the device. While the wheels may be driven me-

chanically, a satisfactory manual drive is shown which includes a pair of gears 14 in mesh with peripheral gear teeth on the wheels 12. The gears 14 are mounted on a rod 15, one end of which is provided with a crank handle 16. The rotation of wheels 12 thus effects the ordered movement of the bars 10 while the latter, through their respective engagements with the filtering material and the unit, operate to pull the filtering material from the roll as needed and to move 10 the unit through the device.

Operation

With an air-filter unit frame F, or the corrugated filter-medium support of an air filter, properly placed on the track at the inlet side of the loading area of the device and with a roll of filtering material in place the operation of the device can be instituted by pulling one end of the roll downwardly between the unit and the operating bars 10, moving the unit inwardly manually or otherwise until it presses the filtering material against a bar 10 and then turning the handle 16 to rotate the wheels 12 in the indicated direction of rotation. At the start, either 25 an excess of filtering material should be provided at the forward end of the air filter unit, or, the filtering material should be clamped between the front end of the unit and one of the bars 10 until a bar passes downwardly into the first corrugation sufficiently to clamp the filtering material at the bottom thereof. With the filtering material thus clamped, successive portions of it can be easily and quickly conformed to successive corrugations and the filter unit frame moved 30 through the device simply by turning the crank handle 16. It is possible also to load a succession of frames simply by feeding one frame after another to the device. Of course, it will be necessary to cut the filtering material at the end of 35 one loaded frame or between loaded frames.

Having described my invention, I claim:

1. A loader for air filters of the type having a corrugated filter-medium support, said loader having a loading area through which said support passes, during the loading operation, with its corrugations extending sequentially along the line of motion, comprising: a frame; a series of operating elements extending transversely of said line of motion; element engaging guide means mounted on said frame to guide said elements along prescribed paths extending into and out of said loading area; and means for moving said elements along said paths and in a sequence such that successive elements are adapted to enter successive corrugations of a support passing through the loading area, pass to the bottom thereof and remain at the bottom until the succeeding element enters and passes substantially to the bottom of the succeeding corrugation. 50

2. The loader of claim 1, wherein: said elements upon entering successive corrugations are adapted successively to engage a support in the loading area; and said moving means is operative, through such engagements, to move said support through said loading area. 60

3. The loader of claim 1, wherein said guide means prescribe the same endless path for all elements, said path comprises the following successive portions: a pressing portion which enters 70 the loading area and extends into the path followed by the bottoms of the corrugations of a support therein; a holding portion which extends forwardly along said path in the direction of motion for a distance not appreciably less than 75

the pitch of said corrugations; an exit portion which extends out of the loading area from the holding portion; and a return portion which extends from the exit portion to the pressing portion.

4. The loader of claim 1 wherein: said moving means includes a control part rotatably mounted on the frame and having a series of uniformly spaced, outwardly extending slots through each of which one operating element extends.

5. A loader for air filters of the type having a corrugated filter-medium support, said loader having a loading area through which said support passes during the loading operation, with its corrugations extending sequentially along the line of motion, comprising: a frame; a series of operating elements extending transversely of the line of motion; means on said frame defining, on opposite sides of said loading area, opposed endless channels into which each of said elements extend, said channels cooperating to prescribe a path along which the elements may move, said path extending into and out of said loading area; and means for moving said elements along said channels and in a sequence such that they are adapted successively to enter successive corrugations of a support passing through the loading area, pass to the bottom thereof and remain at the bottom until the succeeding element enters and passes substantially to the bottom of the succeeding corrugation.

6. The loader of claim 5, wherein said elements are relatively movable and wherein the path defined by said channels includes successive portions which slant forwardly into the loading area, extend forwardly along the line of motion for a distance not appreciably less than the pitch of said corrugations, and slant forwardly out of the loading area.

7. An air filter loader comprising: a frame upon and along which may be supported and moved a member presenting an outwardly facing corrugated face, the corrugations of which extend successively in the direction of movement; means on said supporting frame extending across the path of movement of said member; said means including a series of relatively movable elements adapted for successive movement along a predetermined endless path, a portion of which extends inwardly into the path of movement of said member and substantially to the bottom plane of its corrugations, forwardly along said plane for a distance not appreciably less than the pitch of said corrugation, and thence outwardly from said path of member movement; means for moving said member forwardly along its path of movement from one side of said elements to the other side thereof; and means for moving said elements successively along said endless path and in a sequence such that each element enters the bottom plane portion of said endless path before the preceding element leaves such portion; said elements being adapted, during movement and after one corrugation of said member has been moved into the path of inward movement of one

element, to move successively into successive corrugations of said member.

8. An air filter loader comprising: a frame upon and along which may be supported and moved a member presenting an outwardly facing corrugated face, the corrugations of which extend successively along its path of movement; means on said frame defining, on opposite sides of said path, opposed endless channels, corresponding portion of which extend inwardly into said path substantially to the bottom plane of said corrugations, forwardly along said plane and thence outwardly from said path; a series of bars having their opposite ends extending into said opposed channels, said bars being adapted for successive movement along the path prescribed by said channels; means for moving said bars successively along said channels and in a sequence such that each bar enters said bottom plane portion before the preceding bar leaves such portion, said means comprising a control part mounted rotatably on said supporting frame over each of said channels on the outer side of the bottom plane portion thereof, each control part having a series of uniformly spaced, outwardly extending slots through each of which one bar extends; and means for rotating said control part; said bars being operative, during movement and after one corrugation of said member has been moved into the path of inward movement of one bar, to effect the forward movement of said member and to move successively into successive corrugations thereof.

9. An air filter loader comprising: a frame on which may be supported a member presenting a corrugated face, said member being adapted to receive a sheet of material over its face; a series of relatively movable operating elements mounted on said frame and adapted for movement along prescribed paths, said elements being further adapted, when moved, to press successive portions of said sheet successively to the bottom of successive corrugations and to hold each portion at the bottom until the next succeeding portion has been pressed substantially to the bottom of the next succeeding corrugation; and means for moving said elements.

10. An air filter loader comprising: a frame on which may be supported a member presenting a corrugated face, said member being adapted to receive a sheet of material over its face; a series of relatively movable operating elements mounted on said frame and adapted for movement along prescribed paths, each element being further adapted, when moved, to enter and pass to the bottom of a corrugation and subsequently to move outwardly therefrom; and means for moving said elements successively into successive corrugations and in a sequence such that one element closely approaches the bottom of its corrugation before the succeeding element enters the succeeding corrugation and then remains at the bottom until the succeeding element closely approaches the bottom of its corrugation.

THOMAS R. HUGHES.
